UNITED STATES PATENT OFFICE.

NAPOLEON DU BRUL, OF CINCINNATI, OHIO.

DESIGN FOR A TABLE FOR CIGAR-WRAPPER-CUTTING MACHINES.

SPECIFICATION forming part of Design No. 28,292, dated February 15, 1898.

Application filed January 7, 1898. Serial No. 665,983. Term of patent 14 years.

To all whom it may concern:

Be it known that I, NAPOLEON DU BRUL, a citizen of the United States, and a resident of Cincinnati, in the county of Hamilton and

5 State of Ohio, have invented and produced a new and original Design for a Table for Cigar and Cigarette Wrapper Cutting Machines, of which the following is a specification, reference being had to the accompanying drawing, to forming a part thereof.

The drawing is a perspective view of the table for a cigar and cigarette wrapper cutting machine, showing my design.

The leading or material feature of my de-

sign is a table having a rectangularly-shaped 15 box or chamber.

The table has at one side a rectangularly-shaped box or chamber.

Having now described my invention, what I claim as new, and desire to secure by Letters 20 Patent, is—

The design for a table for cigar-wrapper-cutting machines, substantially as herein shown and described.

NAPOLEON DU BRUL.
